(57) **CLAIM**

The ornamental design for an inflatable leg rest, as shown and described.

DESCRIPTION

FIG. 1 is a front perspective view of an inflatable leg rest, showing our new design;

FIG. 2 is a front view thereof;

FIG. 3 is a rear view thereof;

FIG. 4 is a side view thereof;

FIG. 5 is an opposing side view thereof;

FIG. 6 is a top view thereof; and,

FIG. 7 is a bottom view thereof.

The broken lines are included for the purpose of illustrating environmental portions of the inflatable leg rest that form no part of the claimed design.
